WELL FLOWING APPARATUS

James O. Lewis, Houston, Tex., assignor, by direct and mesne assignments, of one-half to E. C. Will and one-sixth to P. R. Haas, both of Corpus Christi, Tex.

Application December 18, 1940, Serial No. 370,611

6 Claims. (Cl. 166—2)

1

My invention relates to a well flowing apparatus, particularly for handling the well fluids produced from two or more producing horizons of a well. For example, many oil and gas fields have more than one producing horizon, but obtaining this production through a common well results in waste and is prohibited by laws of most states, in which case it is necessary either to produce first from one horizon until it is exhausted and then the other, or to drill separate wells to each horizon. The first alternative delays the recovery of the oil and/or gas from the field while the second increases the cost of development. In order to overcome these objections attempts have been made to separate the horizons by means of a packer set on an inner string of pipe and arranged to sealingly engage the casing or wall of the bore-hole so that production from one horizon is produced through the pipe while the production from the other horizon flows through the annular space between the casing or walls of the bore-hole and the pipe, but with this method liquids and sediments accumulate in the annular space until they overcome the natural pressure and prevent further flow. Even so-called dry gas contains some water and gasoline vapor which will condense long before the field has been exhausted, preventing further recovery. This method is also not satisfactory when the volume or the natural pressure is insufficient to flow the liquids to the earth's surface.

It is, therefore, a principal object of the present invention to provide a well flowing apparatus whereby oil and/or gas may be successfully and economically produced from a plurality of formations through a common well.

Other objects of the invention are to provide a well flowing apparatus for selectively and separately handling the various conditions and problems encountered in producing fluids from two or more production horizons through which a well is drilled; to provide a flowing apparatus whereby accumulations of liquids or sediments may be readily discharged under natural well pressures or aided by the introduction of pressure from the surface of the well; to provide a flowing apparatus whereby gas from a high pressure horizon may be utilized to aid in flow of fluid from a low pressure horizon; to provide an apparatus whereby fluids may be introduced into the well for displacing drilling fluid until the column of liquid has been lightened sufficiently so that it will flow by natural pressure or by gas or air pressure applied from the surface of the well; and to provide a well flowing apparatus

2

whereby heavy fluids may be introduced for "killing" flow from one or both formations when desired to repair or service the well.

It is also an object of the invention to provide a well flowing apparatus wherewith acid, wash fluids, gas, or other medium may be selectively introduced to the producing formations for opening the pores and making the well more productive; and to provide for circulation of fluid to remove paraffin or other substances clinging to the walls and tubing of the well.

A further object of the invention is to provide a well flowing apparatus whereby flow may be separately and selectively maintained under natural pressure and which is adapted for the installation of pumps when the natural pressure drops below that required to lift the fluid.

In accomplishing these and other objects of the invention, I have provided improved details of structure, the preferred form of which is illustrated in the accompanying drawings, wherein:

Fig. 1 is a longitudinal sectional view through a well equipped with a flowing apparatus for separately and selectively controlling flow from a plurality of producing horizons through which the well is drilled.

Fig. 2 is an enlarged elevational view of the flowing apparatus at the head of the well, particularly illustrating the jacks for selectively positioning the transfer valve.

Fig. 3 is an enlarged vertical section through the lower portion of the well illustrating the transfer valve in position for valving off flow from an upper formation.

Fig. 4 is a similar section showing the transfer valve in position for establishing flow from the upper formation.

Fig. 5 is a cross-section on the line 5—5 of Fig. 3.

Fig. 6 is a cross-section on the line 6—6 of Fig. 3.

Fig. 7 is a cross-section on the line 7—7 of Fig. 4.

Fig. 8 is a vertical section through a modified form of the mechanism for positioning the control or transfer valve.

Fig. 9 is a cross-section on the line 9—9 of Fig. 8.

Fig. 10 is an enlarged section through a modified form of control valve.

Fig. 11 is a similar section through a further modified form of valve.

Fig. 12 is a cross-section on the line 12—12 of Fig. 11.

Fig. 13 is a cross-section on the line 13—13 of Fig. 11.

Fig. 14 is a vertical section through a further modified form of valve.

Fig. 15 is a cross-section on the line 15—15 of Fig. 14.

Referring more in detail to the drawings:

1 designates the bore-hole of a well drilled through a plurality of producing formations 2 and 3 located at different horizons. The well is cased by a casing 4 having perforations in the portions thereof extending through the producing formations as indicated at 5 and 6. The upper end of the casing is provided with a cap 7 having a side connection 8 which is provided with a valve 9 to control flow of fluids therethrough, as later described.

Extending within the casing to a point intermediate the producing formations is a pipe inner casing or production string 10 carrying a packer 11 which sealingly engages the wall of the well or the casing 4 for separating flow from the upper and lower formations 2 and 3. The pipe 10 is of smaller diameter than the casing to provide a flow passageway 12 therebetween, and to permit the flow of fluid from the upper formation to the top of the well or into a transfer valve or control coupling 13 which is inserted between sections of the pipe 10 substantially at the level of the producing formation 2. The upper end of the pipe 10 projects through the cap 7 and carries a lateral connection 14 to which is connected a pipe 15 provided with a control valve 16. Carried by the pipe, above the lateral connection 14, is a blow-out preventer 17, having rams 18 adapted to clamp an inner pipe or duct 19 which extends downwardly into the well and connects with the valving element of the transfer valve 13. The upper end of the inner pipe projects through a stuffing box 20 carried by the blow-out preventer, and carries a cross-fitting 21 having a lateral connection 22 with a pipe 23 that is provided with a control valve 24. The upper branch 25 of the cross-fitting is also shown as connected with a pipe 26 through a control valve 27, the other branch 28 being closed by a plate 29.

The preferred form of transfer valve 13 is best illustrated in Fig. 3, and includes a sleeve-like valve body 30 having internally threaded sockets 31 and 32 at the respective ends thereof to threadedly engage the adjacent ends 33 and 34 of the pipe sections composing the pipe 10. Extending axially through the sleeve-like body is a bore 35 shaped to provide intermediate of the body an internal annular recess 39 and vertically spaced inwardly extending guide ribs 36 and 37 positioned respectively above and below said recess. One or more radially disposed inlet openings 38 extend from the annular recess 39 between the guide ribs 36 and 37 through the exterior face of the valve body. An internal guide face 40 on the lower rib 37 is of smaller diameter than a corresponding guide face 41 on the upper rib, and said faces slidingly engage the different diametered upper and lower portions 42 and 43 respectively of a valving member 44, and to provide a bevelled seat 45 on the guide rib 37 which is adapted to engage a bevelled shoulder 46 on the member 44 formed between the respective different diametered portions thereon. The under face 47 of the lower rib is also bevelled to provide a seat 48 adapted to be engaged by a bevelled shoulder 49 formed on the end of a sleeve 50, which is threaded over a reduced lower end 51 of the valving member. The bevelled faces 45 and 49 of the

valving member are thus oppositely disposed and spaced apart to provide the required movement of the valving member to bring a port 52 therein from registry with the openings 38 to a point below the lower guide rib when the shoulder 45 engages the seat 46. The upper end of the valving member 44 projects above the guide rib 36 and extends through a packing 53 that is positioned in a recess 54 in the valve body and compressed against the valving member by a follower 55 having external threads engaging internal threads at the upper end of the recess 54 as shown in Fig. 3, the ring elements of the packing being preferably of C-shaped cross-section with one group arranged with the lips facing downwardly and another group with the lips facing upwardly to seal in both directions.

The valving member is provided with an axial bore 56 extending from the upper end thereof to below the port 52, as shown in Fig. 3. The upper end of the bore is preferably tapered and internally threaded, as at 57, to engage the threaded pin 58 of a coupling member 59, the coupling member in turn being provided with an internally threaded box 60 in which the lower end of the pipe 19 is threaded.

In order to raise and lower the valve, I provide a hydraulic mechanism 61 located at the top of the well and adapted to grippingly support the projecting end of the inner pipe. The hydraulic mechanism includes a pair of cylinders 62 having piston-like rods 63 movable therein and connected by a cross-yoke 64. The cross-yoke 64 has a central clamp collar 65 for engaging between collars 66 and 67 on the pipe 19. A fluid medium is admitted to the lower end of the cylinders through ducts 68 under control of valves 69.

The blow-out preventer includes a substantially cross-shaped body 70, having the rams 71 slidably mounted in the horizontal arms 71 thereof which are manipulated by screws 72 to move the rams to and from engagement with the pipe. The rams of the blow-out preventer thus prevent escape of fluids in case the packing of the stuffing box 20 should fail and serve as an added precaution for control of the well and prevent accidents. In order that the fluid from the lower strata 3 may by-pass the transfer valve, the body thereof is provided with a plurality of openings 73 interconnecting the sockets 31 and 32 of the transfer valve body.

When the shoulder 45 is engaging the seat 46, no fluid can pass from the upper formation 2 into the center pipe 19, but fluid can flow from the lower formation 3 through the lower portion of the pipe 10 below the valve, port 52, and through the center pipe 19 to the top of the well. When it is desired to provide flow from the upper formation and to shut off flow from the lower formation through the center pipe 19, the rams 18 are loosened and the hydraulic valves 69 are opened to admit pressure fluid to the lower end of the hydraulic cylinders 62 for raising the pistons 63 and effecting lift of the pipe 19 which carries the valving member 44 from engagement with the seat 46 to effect engagement of the shoulder 49 thereof with the seat 48. This movement of the valving member brings the port 52 thereof in registry with the opening 38, as shown in Fig. 4, so that flow is established from the upper formation through the ports 38 and 52 into the center pipe 19.

It will be the usual practice to flow both formations simultaneously. Flow from the upper

formation passes through the casing 4 and is discharged through the branch 8 upon opening of the valve 9 and the flow from the lower formation passes through the packer 11 around the transfer valve through the by-pass or ports 13, and through the pipe 10 for discharge through the branch 15 upon opening of the valve 16. In this case the pipe 19 will be used only to flow out liquid that has accumulated from either sand when the pressure is not sufficient to effect natural flow thereof from the well. The accumulating fluid, however, will flow readily through the pipe 19 because of its smaller diameter, and the flow will be at higher velocity to lift the liquid. When flow is to be established from the upper sand into the pipe 19, the valve is shifted to the position shown in Fig 4, and when flow is to be established therethrough from the lower formation the valve is shifted to the position shown in Fig. 3. The pipe 19 may thus be used to alternately lift liquid from the upper and lower formations by changing positions of the valve as shown in Figs. 3 and 4. If it is desired to discharge all of the liquid through the center pipe, the valves 9 and 16 will be closed and the fluid from the respective stages is alternately flowed by properly positioning the transfer valve. It is thus obvious that with the structure illustrated and described, both formations may be flowed simultaneously through the casing 4 and pipe 10, or through the casing 4 and pipe 19, or the pipes 10 and 19, or flow may occur through both the casing 4 and pipe 10 while a flow is being maintained from one or the other of the sands through the pipe 19. Thus the well may be flowed in various ways. If desired, an external gas from other sources may be introduced to either the space 12 or to the lower part of the pipe 10 through the central pipe 19 to help lift the fluids when the natural pressures become inadequate.

When a well is completed by rotary drilling methods, lighter fluids such as clear water, oil, or gas may be introduced through the center pipe 19, into either the inner or outer pipes 10 and 4 from the top of the well while the drilling fluid is displaced out through the annular spaces.

When repairing the well, the pressure thereof may be "killed" by introducing heavy fluids into the central pipe 19 and the well fluids displaced through the casing 4 or pipe 10 by properly positioning the transfer valve, or the heavy fluids can be introduced and the light fluids displaced in reverse manner.

The apparatus also provides for treating either horizon with acids, wash liquids, or other fluids to open up pores of the producing formation to make it more productive. Should the pressure in both formations become too low to flow the liquids, the central pipe 19 may be equipped with the usual type of deep well pumps and either formation pumped, depending upon the position of the transfer valve member 44. In a similar manner a swab or bailer can be run into the central pipe 19 to remove liquid collecting therein from either formation, depending upon the position of the valving member 44.

In the form of the invention shown in Fig. 8, the stuffing box mounted on the blow-out preventer carries a hydraulic cylinder 74 on spacers 75 which accommodate space for the packing glands 76 and 77. The inner or center pipe 78, which is equivalent to the pipe 19, extends through the cylinder 74, and interposed therein is a piston 79. Connected with the cylinder 74,

at a point below the lowermost position of the piston 79, is a valve controlled pipe 80 through which a pressure fluid is admitted to the lower end of the cylinder for raising the transfer valve. 5 Mounted on the head 81 of the cylinder, on similar spacing devices 82, is a pipe 83 carrying a cross-fitting 84 having discharge outlets 85 and 86 complementary to the discharge outlets 23 and 26 of the first described form of the invention. The upper end of the pipe 78 moves within the pipe 83 and is sealed therewith by a packing box 87 fixed to the pipe 83. Otherwise the construction is the same as that disclosed in the first form of the invention and operates in the same manner.

In Fig. 10 is illustrated a modified form of transfer valve. In this form of the invention the valve member 88 includes a tubular section 99 slidable through the body 98 of the valve, and 20 which has a port 91 adapted to move into and out of registry with the lateral port 92 in the valve body. The lower end of the tube-like valve 89 is closed by a plug 93 and the upper end is connected with the lower end of the pipe 19 by a coupling 94. The valving member is packed on each side of the inlet port 92 by packing elements 95 and 96 received in annular recesses 97 and 97' in the bore of the valve body 98. If it is found necessary, the tubing 19 may be equipped with a pump mechanism whereby the liquid passing thereinto may be lifted to the top of the well.

The transfer valve shown in Fig. 11 is of the rotary type and includes a conical shaped hollow core 98 rotatable in a tapered bore 99 in the valve body 100 to one position to connect a lateral port 102 in the core with a lateral port 101 in the valve body which admits fluid from the upper formation, or to connect port 102 with a port 103 in the valve body which connects with a passageway 104 extending longitudinally of the body of the valve. When desired to flow from the upper formation, the valve core 98 is rotated by rotating the tubing 105 connected thereto so that the port 102 in the core communicates with the lateral port 101. When it is desired to flow from the lower formation, the valve is rotated so that the port 102 therein registers with the port 103, and the flow is from the lower formation through the passageway 104 into the central pipe. 45 50 In order to limit the stop positions of the valve, the valve core is provided with lateral lugs 106 and 107 engageable with an inwardly extending lug 108 formed in the bottom of the upper recess 109 in valve body 100, the upper end of which recess is threaded to receive the upper section of pipe in the outer string 110.

The form of transfer valve shown in Fig. 14 differs from the form shown in Fig. 1, in that the lower end of valving member 44' has a threaded neck 111 which carries a hollow guide coupling 112 which is slidable in a cylindrical recess 113 formed in the bottom of the valve body 30' and which carries a depending tube 114 forming a continuation of the upper tube 19 so that the flow from the formation below the valve may be effected through the depending tube and passed through ports 115 formed in an upper beveled seat 49' on the coupling and through the lateral port 52' of the valving member 44' for flow upwardly through the central pipe 19. When the pipe 19 is lifted, flow through the depending pipe 114 is cut off by the engagement of the upper seat 49' on coupling 112 with a corresponding downwardly facing beveled seat 48' on lower rib 75 78' covering ports 115.

What I claim and desire to secure by Letters Patent is:

1. In an apparatus of the character described, a transfer valve including a body having spaced guides therein and an inlet port between said guides, and a valving member slidably in said guides and having shoulders for respectively engaging opposite sides of one of the guides and provided with a passageway adapted to connect with said port when one of the shoulders engages said guide, said valving member being arranged to close said port when the other shoulder engages the guide, said valve body having a bypass for directing fluid around the valving member.

2. In an apparatus for producing a well from a plurality of production formations, packer means for separating the production formations, separate conduits extending from the upper end of the well to each production formation, means at the surface to selectively close or open each conduit, a tubing extending into the well inside of said conduits, means for selectively and separately connecting the tubing with the respective production formations so as to flow that production formation either through its conduit or through the tubing, or to so connect the tubing as to simultaneously flow the formation from its conduit and the tubing without interfering with the separate flows from the other production formations through their conduits, there being no commingling of fluids from different production formations.

3. An apparatus for producing a well from two formations independently and without commingling of fluids where one formation has a casing extending thereto which comprises, an inlet into said casing from that formation, a production string of pipe and a cooperative packer thereon to seal with said casing between the formations, an inlet from the other formations to said production string, a string of tubing in said production string, a transfer valve adapted to admit a flow to said tubing through either said casing and one formation, or through the production string and the other formation without interfering with the flow of the other formation,

and means at the surface to manipulate said tubing to open or close said transfer valve as to either formation.

4. A well having a bore which intersects a plurality of gas and liquid bearing formations, pipe members within the bore subdividing the same into separate chambers each extending downward from adjacent the ground level and each having means for admitting fluids thereto from one of the formations, each chamber being adapted to flow fluids independently to the surface, a tubing in the well of smaller cross section than either chamber and adapted to be connected alternatively and selectively with one of said chambers while sealed from the others, whereby the liquids can be siphoned from the well without interfering with the flow of fluids through any of the chambers or causing commingling of fluids from different formations.

5. A well having a bore which intersects a plurality of gas and liquid bearing formations, pipe members within the bore subdividing the same into separate chambers, each extending downward from adjacent the ground level and each having means for admitting fluids thereto from one of the formations each chamber being adapted to flow fluids independently to the surface, a tubing in the well adapted to be connected alternatively and selectively with one of said chambers while sealed from the others whereby fluids under pressure can be introduced from an exterior source into either the tubing or the chamber to which it is connected to facilitate flow through the chamber or the tubing without interfering with the flow through the other chambers or commingling of the fluids therein.

6. In a well equipped with pipes to provide separate conduits to the surface for each of a plurality of separated formations, a string of tubing in the innermost pipe, an inlet to the tubing from each pipe, means to move the tubing to connect with either of said inlets, pumping means in the tubing to lift liquids to the surface without interfering with the separate flow of liquids through said conduits.

JAMES O. LEWIS.
